UNITED STATES PATENT OFFICE.

LAWRENCE A. KIANDER, OF NEW YORK, N. Y.

ART OF DENTAL SURGERY.

Application filed March 16, 1922. Serial No. 544,372.

To all whom it may concern:

Be it known that I, LAWRENCE A. KIANDER, a citizen of the United States, and residing at New York, in the county of New York and State of New York, have invented certain new and useful Improvements in the Art of Dental Surgery, of which the following is a specification, such as will enable those skilled in the art to which it applies to make and use the same.

This invention relates to the art of dental surgery and particularly to what is known as artificial dentures or bridge and plate work in such art, and the object of the invention is to provide means for making bridge or plate work more effective, practical and efficient in use and to avoid the capping or crowning of permanent teeth in what is known popularly as bridge-work at the present and, in which, by means of my improvement, bridge-work as well as plate-work may be detachably connected with the permanent teeth instead of being rigidly secured thereto as is the general custom; a further object of the invention is to provide a denture of the class described with a clasp so mounted in connection with the denture as to permit of the movement of said clasp thereon to facilitate the mounting of the denture upon the permanent teeth of a jaw regardless of the position of such teeth in the jaw and to permit of the removal of such bridge or plate work without injury in any way to the permanent or natural teeth; and with these and other objects in view the invention consists in an artificial denture of the class and for the purpose specified which is simple in construction, efficient in use and constructed as hereinafter described and claimed.

The invention described and claimed herein is an improvement on that shown and described in a prior patent granted to me February 28, 1922, No. 1,408,006, and is fully disclosed in the following specification, of which the accompanying drawing forms a part, in which the separate parts of my improvement are designated by suitable reference characters in each of the views, and in which:

Fig. 1 is a side view of a part of a jaw showing my improved artificial denture mounted in connection with two of the natural or permanent teeth thereof;

Fig. 2 a bottom plan view of the construction shown in Fig. 1;

Fig. 3 a partial section on the line 3—3 of Fig. 2 of the artificial denture detached and on an enlarged scale;

Fig. 4 a partial section on the line 4—4 60 of Fig. 3 on an enlarged scale;

Fig. 5 a partial section on the line 5—5 of Fig. 3 on an enlarged scale;

Fig. 6 a perspective detail view of the movable clasp employed; 65

Fig. 7 a perspective detail view of a pin or part employed;

Fig. 8 a perspective detail view of a plate employed;

Fig. 9 a perspective detail view of a shield member employed; 70

Fig. 10 a view similar to Fig. 4 with part of the construction omitted and showing a modification; and,

Fig. 11 a view similar to Fig. 10 but showing another modification. 75

In Fig. 1 of the drawing I have shown at 12 a part of a jaw provided with two permanent or natural teeth 13 and 14 and at 15 is shown my improved denture comprising a plate 16 of the usual or any desired form and construction to which, in the construction shown, is secured two artificial teeth 17, and the plate 16 at one end of the denture is provided with a permanent clasp device 18 having two teeth encircling prongs 19 and an inwardly directed part 20 adapted to sit in the outer face of the tooth 13 as clearly shown in Fig. 2 of the drawing. Mounted in connection with the other end of the denture is a movable clasp device 21 shown in detail in Fig. 6 of the drawing, said clasp being provided with teeth engaging prongs 22 adapted to encircle or partially encircle the tooth 14 as shown in Figs. 1 85 and 2 and with a central bridge member 23 adapted to rest upon the face of the tooth as shown in Fig. 2, and the cross head portion of the clasp 21 is provided with an aperture 24 adapted to receive the shank of a pin or part 25 shown in detail in Fig. 7. 90

The pin or part 25 is provided with an enlarged head 26 and, in the construction shown in Figs. 1 to 9 inclusive, the head 26 is cut away as shown at 27. In mounting the clasp 21 in connection with the denture 15 I employ an attaching plate 28 and shield member 29 shown in detail in Figs. 8 and 9 of the drawing. The plate 28 may be provided at its upper edge with an elongated aperture 30 open outwardly therethrough and said aperture is enlarged to form a sub-

stantially circular aperture 31. The shield member 29 is of less vertical demensions than the plate 28, and approximately the same transverse dimensions as said plate and is provided with a recess 32 on the inner face thereof to receive the head 26 of the pin or part 25, and the top portion 33 of the member 29 is provided with a rectangular projection 34 adapted to enter the aperture 32 in the plate 28 as shown in Figs. 3, 10 and 5 of the drawing.

In attaching the clasp 21 to one of the artificial teeth a recess 35 is formed on the edge of such tooth as shown in Fig. 3 of 15 the drawing. The attaching plate 28 and shield member 29 are connected or placed one upon another with the head 26 of the pin or part 25 within the recess 32 and with the shank of said pin or part projecting through the aperture 31 in the plate 28, and said parts thus connected are placed in the recess 35 and are secured in position by soldering or otherwise, in which the surrounding body 36 of the plate 16 of the 20 denture securely holds and retains the parts 28 and 29 in connection therewith, and the rectangular projection 34 on the shield member 29 prevents solder or the like from passing down around the pin or part 25 or into the recess 32 which would effect the 25 operation of said pin or part, and also serves to limit the upward movement of the pin or part in its supports. The clasp 21 may now be secured to the projecting portion of the 30 pin or part by riveting, soldering or otherwise, and after the usual grinding and finishing of the complete denture the same will be ready for use.

In applying the denture in the mouth or 40 mounting the same upon the natural teeth 13 and 14, it will be apparent that the clasp 21 will be free to oscillate in the denture proper as well as free to move vertically and laterally therein by reason of the clearance allowed between the shank of the pin or part 25 and the aperture 31, as clearly shown at 37 in Fig. 5 of the drawing. The oscillatory movement of the clasp will be limited in the construction shown in Fig. 4 by the 45 cut off portions 27 of the head 26 striking the top wall of the recess 32 in the shield member 29 as will be apparent. This construction will provide a smooth and unobstructed outer face to the denture where the 50 movable clasp 21 is mounted in connection therewith, and while I have specified a specific manner of mounting the separate parts 21, 25, 28 and 29 together and to the denture proper, it will be understood that 55 I am not necessarily limited to this method of procedure as said parts may be connected in any desired manner.

In Fig. 10 of the drawing, I have shown a slight modification in which the head 26 60 of the pin or part 25 is cut away as shown

at 38 and the upper wall of the recess 32 is made V-shaped in form as shown at 39 to permit of the oscillation of the pin, or the head 26 thereof, in the recess 32. In Fig. 11, however, I have shown the pin or 70 part 25 provided with a circular head 26 and in this form of construction the entire clasp and pin will be free to rotate upon the denture instead of being capable of an oscillatory movement only as in Figs. 4 and 75 10.

It will be apparent that while I have shown a specific form of denture, bridge or plate work that I am not necessarily limited to the character of denture employed, 80 the invention consisting in the method of mounting a movable clasp in connection with any kind or class of artificial denture, and various changes in and modifications of the construction herein shown and described may be made, within the scope of 85 the appended claims, without departing from the spirit of my invention or sacrificing its advantages.

Having fully described my invention, 90 what I claim as new and desire to secure by Letters Patent is:—

1. In an artificial denture device, a denture body, an attaching plate and a shield member mounted in connection with each other 95 to form a recess therebetween, said plate and member when connected being adapted to be secured to the denture body, a pin or part loosely mounted in connection with said plate and member and provided with an enlarged head located in said recess, the shank of said pin or part projecting through 100 said plate, and a tooth clasp secured to the projecting portion of said pin or part.

2. In an artificial denture device, a denture body, an attaching plate, and a shield member mounted in connection with each other to form a recess therebetween, said plate and member when connected being adapted 105 to be secured to the denture body, a pin or part loosely mounted in connection with said plate and member and provided with an enlarged head located in said recess, the shank of said pin or part projecting through 110 said plate, and a tooth clasp secured to the projecting portion of said pin or part whereby 115 said tooth clasp and pin or part are loosely mounted in connection with said denture body.

3. The herein described means for mounting a movable clasp in connection with a denture body comprising a unit composed of separate parts adapted to be imbedded in said denture body, and a pin or part permanently retained in and loosely mounted 125 in connection with said unit and projecting therefrom.

4. The herein described means for mounting a movable clasp in connection with a denture body, comprising a unit composed of 130

an attaching plate and shield member adapted to be imbedded in said denture body, and a headed pin or part adapted to be permanently retained in said unit and 5 loosely mounted therein.

5. A movable clasp mounting for artificial dentures of the class described comprising an attaching plate, shield member and a pin or part, said parts being adapted to be 10 connected in such manner as to retain the pin or part in and between said attaching plate and shield member with the pin or part projecting therefrom and capable of movement therein.

15 6. A movable clasp mounting for artificial dentures of the class described comprising an attaching plate, shield member and a pin or part, said parts being adapted to be connected in such manner as to retain the pin 20 or part in and between said attaching plate and shield member with the pin or part projecting therefrom and capable of movement therein, and a tooth clasp adapted to be secured to the projecting portion of said pin or part.

25 7. A movable clasp mounting for artificial dentures of the class described comprising an attaching plate, shield member and a pin or part, said plate being provided with an 30 elongated aperture enlarged at its inner end, said member being provided with a recess and with a projection adapted to enter a part of the aperture of said plate and said pin or part being provided with a head 35 adapted to be located in the recess of said member and with a shank projecting loosely through the enlargement of the aperture in said plate.

30 8. A movable clasp mounting for artificial dentures of the class described comprising

an attaching plate, shield member and a pin or part, said plate being provided with an elongated aperture enlarged at the inner end, said member being provided with a recess and with a projection adapted to enter a 45 part of the aperture of said plate and said pin or part being provided with a head adapted to be located in the recess of said member and with a shank projecting loosely through the enlargement of the aperture in 50 said plate, and a tooth clasp adapted to be secured to the shank of said pin or part.

55 9. The combination with an artificial denture device of the class described, of means comprising connected members 55 adapted to be embedded in and secured to said denture body, a pin or part loosely supported in connection therewith, said pin or part being contained within said means and projecting therefrom, and a tooth clasp 60 mounted on the projecting portion of said pin or part.

65 10. The combination with an artificial denture device of the class described, of means comprising connected members 65 adapted to be embedded in and secured to said denture body, a pin or part loosely supported in connection therewith, said pin or part being contained within said means and projecting therefrom, a tooth clasp 70 mounted on the projecting portion of said pin or part, and means on said pin or part within said first named means and cooperating therewith for limiting the movement of said pin or part in predetermined directions. 75

In testimony that I claim the foregoing as my invention I have signed my name this 15th day of March, 1922.

LAWRENCE A. KIANDER.
